COP SPOOLING MACHINE

Wilhelm Reiners and Gustav Kahlisch, Gladbach-Rheydt, Germany, assignors to W. Schlaflhorst & Co., Gladbach-Rheydt, Germany, a corporation of Germany

Application June 21, 1932, Serial No. 618,554
In Germany June 29, 1931

11 Claims. (Cl. 242—35.5)

There are some cop spooling machines in which the winding on all the spindles or at any rate on a group of spindles is started and stopped simultaneously, in the entire machine; or the group of spindles is stopped in order to remove the cops and put on new tubes. This has hitherto been done by hand, and necessitates a relatively long stoppage of the spindles, with consequent reduction of efficiency as regards the output of the machine.

10 In connection with ring spinning, certain devices have been contrived for the purpose of taking off the full spools or cops and putting on the tubes in groups, the full spools being lifted by means of forks fitted with pins, or by grippers. 15 The disadvantage of these arrangements is that in some respects they interfere with the operation of the machine, as they are more or less in the way of the operator, even if during normal working they are removed from close proximity to the spindles. This renders it almost wholly impracticable to apply them to spooling machines, owing to the greater strain on the thread, which causes far more breakages of thread and other troubles 20 in winding, which must be rectified by the operator during the working of the spindles.

The importance of simultaneous removal of finished cops followed by a simultaneous mechanical slipping on of the empty tubes is very great, as it produces a relatively large saving of time and increased output, particularly when a small quantity of thread is wound on each cop. Cops having very little material thereon are now used in the case of artificial silk, and also natural silk.

35 In connection with twisting machines it has been proposed to use a conveyor band which can be raised and lowered to lift the empty twist rollers into the plane of the retractable spooling spindles (which can also be drawn) to take up the released full rolls of twist and to place the empty ones between the spindles and the centres. A 40 device of this kind, owing to the trouble and expense of fitting it up, cannot be used in cop spooling machines, and also obstructs the view of the process of spooling.

45 The object of our invention is to make it possible to effect simultaneous winding of cops and exchange of cops for empty tubes, in the whole bank of spindles, or any group of spindles, however large, without incurring the disadvantages described above. For this purpose we arrange the cop handling unit outside the area of arrival of the tread, and we provide for relative movement of this unit and the spindles. With the 50 spindles stationary, the cop handling unit may be

movable both transversely of the axis of the spindles and also in the direction of the spindle axis, or it may move only in the axial direction. In the case of axially movable spindles the cop handling unit may be movable transversely of the spindles, and in the case of cop spools which are inserted between the spindles and a back centre, the unit is movable transversely of the spools and also axially.

ing the conveying arrangement for the disposition of the finished cops,

Fig. 24 is an end elevation of Fig. 23,

Fig. 25 is a front elevation of a modified detail 5 of the arrangement shown in Fig. 23.

Several examples of apparatus according to the invention are shown in the annexed drawings.

Figs. 1 to 10 illustrate diagrammatically that 10 form of the device in which the spindles are stationary and the unit X, which serves any desired number of spindles, is movable both transversely of the spindle axis and also in the direction of the spindles.

In Figs. 1 and 2, 1 is the winding spindle, F 15 the thread, 2 the friction wheel seated thereon, which is driven by friction disc 3 mounted on shaft 4. The shaft 4 is driven in the usual way. 5 are the thread guides, which are mounted on a bar 6 in common with all the other thread guides 20 of one side of the machine, or for a group of spindles. The bar 6 is actuated by racks 7 and a pinion 8, the pinion being fixed to a shaft 9. On the same shaft 9 there is fixed a disc 10, with a chain 11 engaging a portion thereof. The chain 25 11 at its upper end also engages with a disc 12, around a portion of the latter. The disc 12 is fixed to a shaft 13. The latter is mounted on a lever 15 pivoted at 14. The lever 15 carries a pin with a roller 16. This roller 16 is moved by 30 a heart-shaped cam 17 on a shaft 18. The shaft 18 is driven by a gear wheel 19 and gear wheels 20 and 21. The gear wheel 21 is mounted on the driving shaft 4. The gear wheel 19 is freely rotatable on its shaft 18, but is restrained from 35 lateral displacement and can be coupled with a collar 22, which is slidable on the shaft 18, to which it is splined. While this coupling 22 is out of engagement the shaft 18 with its heart cam 17, and consequently the entire mechanism 40 11, 10, 9, 8, 7 and 6 is stopped, although the top spindles 1 can continue to rotate. The feed movement of the thread guide 5 takes place in the following way:

On the shaft 13 there is fixed a worm wheel 24, 45 with which engages a worm 25 having its bearing shaft on the lever 15. To the same shaft is fixed a ratchet wheel 26, which is rotated stepwise by a double armed lever 27 and pawl 28, backward rotation being prevented by pawl 29. On each 50 stroke of the lever 15 the lower arm of the lever 27 strikes an adjustable screw 30, so that the swing of the lever can be regulated by adjustment of the screw, and this regulates the angle through which the ratchet wheel is rotated. 55 The chain 11 is wound on to the disc 12 and off the disc 10, and at the same time the shaft 9 with gear wheels 8 is rotated and the racks 7 with the thread guides 5 are shifted. In order to keep the chain 11 taut there is a disc 31 fixed 60 to the shaft 9, with a chain 32 carrying weight 33 attached to its rim. The weight 33 not only keeps the chain 11 taut but also effects the backward movement of the thread guide when pawls 28 and 29 are disengaged and ratchet wheel 26 is rotated backward by its handle 26a.

The cop handling unit, which is designated as a whole by the reference character X in the various figures, is shown in Figures 3 to 10.

The unit X may form a single rigid frame 70 for a plurality of spindles, the longitudinal walls 34a and 34b of the said frame being connected by transverse walls 35. The longitudinal walls are further connected with each other by troughs 36 in the manner of a grating. In these troughs 75 the empty cop tubes 37 are placed ready for

slipping onto the spindles. Centrally between two troughs 36, notches 38 are provided at the upper edge of the longitudinal wall 34b, which, for the purposes of stripping off the full cops 37a from their spindles, engage each bare spindle 5 behind the foot of the cop. The unit X is arranged below the plane of the spindle axes. It rests on rollers 39a and 39b, which are mounted on levers 40a and 40b. The levers 40a and 40b rotate about shafts 41a and 41b. To the shaft 10 41a is fixed a hand lever 42 (Fig. 2). By means of this lever and rods 43, chains, or the like, the unit X can be moved from the position of rest shown in Fig. 3 to the position shown in Figs. 5-10. The shafts 41a and 41b are mounted 15 in the machine frame Y at 44a and 44b (Fig. 1) and are in the form of toothed racks towards the interior of the machine.

The shaft 41a is formed as a toothed shaft at its rear (Fig. 5) and engages with a pinion 45 20 mounted on a shaft 46. This shaft can be rotated by a hand wheel 47 (Figs. 1 and 2), and in this way the body X can be shifted not only vertically but also horizontally, this latter movement being for the purpose of shifting it into the position shown in Figs. 7 and 8, from the position shown in Figs. 5 and 6, after it has received the cops or bobbin tubes. In order to be able to shift the body X lengthwise of the machine it slides with its transverse walls 35 on pins 48a and 48b, 30 for which purpose the transverse walls have a slot 49, of angular form, the vertical part of which serves for the upward movement of the body X, while the horizontal part allows of the forward movement. The longitudinal movement 35 of the part X on the pins 48a and 48b, is limited by suitable stops 50a and 50b. The longitudinal movement of the part X on the rollers 39a and 39b may be effected by hand or by lever mechanism not shown.

The manner of operation is as follows:

In Figs. 3 and 4 the cops 37a on the group of spindles have just been completed. The end thread F is wound around the cop in a steep spiral by a rapid return movement of the thread guide in the manner previously described; on the bare spindle 1 a few turns have been run at 45 1a, so that the thread is held firmly at this point and the cop is ready for stripping off. The part X is in its position of rest beneath the spindle. In the trough 36, a cop tube 37, ready for slipping on to the spindle, is indicated by broken lines.

The operator then raises the unit X vertically upward by the aid of the lever 42, so that the 55 notches 38 in the rear longitudinal wall 34b engage the spindles 1 behind the cops.

As shown in Figs. 7 and 8 the part X has already been shifted forward out of proximity to the spindles by means of the handwheel 47, pinion 45, and the rack portion of shaft 41a (Figs. 1 and 2); during this operation all the cops 37a have been stripped off and have dropped into the box 52 at the bottom of the unit X, from which they can be taken out by hand.

After the cop has been drawn off the spindle, the part X is moved to the extent of about half the pitch of the spindles, see Figs. 8 and 9, so that the empty cop tubes 37 are in line with the spindles.

In Figs. 9 and 10 the part X is moved by wheel 47 towards the interior of the machine for the purpose of putting all the cop tubes 37 jointly and simultaneously on the stationary spindles 1. The part X is now, by the aid of the hand lever 70 75

42, returned to its lower position. The thread guides are now, by means of the ratchet wheel or hand wheel 26 (Figs. 1 and 2), brought back to the starting position for the new winding operation, and the rotation of the spindles 1 is started at the same time by throwing the driving belt 160 by means of belt shifter 161 from the idle pulley 162 to the fixed pulley 163, whereby the thread fixed upon part 1a of the spindle winds around the bare cop tube to begin the winding operation.

When the cops are fully wound the process above described is repeated.

Figs. 11 to 16 illustrate an example in which the spindles are axially movable. Consequently the unit need not be movable in the direction of the spindle axis, its movement transversely of the spindles being sufficient.

The cop handling unit does not in this case differ in its essential parts from the other example described. So far as there are any differences, they merely relate to shape or structure, and adaptation to expediency. Thus, in the example according to Figs. 11 to 14, for instance, the trough 52 intended for the full spools hangs from the shafts 41a, and at the bottom thereof there is a conveyor 99 moved by rollers 99a, so that the spools are conveyed to a collector at the end of the machine. The drive of the conveyor 99 in the trough 52 is shown in Figs. 19 and 20. The special feature of this drive consists in the fact that though it travels with the trough in the direction of the spindle, it always remains in engagement with its prime mover. The driving shaft 4 drives a shaft 100 with a worm 101. The latter engages a worm wheel 102 on a shaft 103, which is mounted in two stationary holders 104. The relatively long part of the shaft 103 between the gearings 104 is toothed.

To the trough 52 two holders 105 are fixed, which serve as bearings for a shaft 106. On this shaft, between the holders 105, there is a roller 99a, which serves to drive conveyor 99. At one end of the shaft 106 there is a pinion 108, which is in constant mesh with the toothed part of the shaft 103, and can move along that part together with the trough 52 and the conveyor 99. From this it is clear that the endless conveyor can be set in motion in any position of the device X. The movement for the conveyor with the full cops takes place during the working of the machine.

The drive of the spindles can in this case be by cords or bands 85 extending between driving pulleys 3c and the driven pulleys 2c. The pulleys 2c are fixed to sleeves 2d having square bores in which spindles 1 can slide longitudinally without being permitted to turn relatively to the sleeve. The spindles furthermore are rotatably mounted in the angle bar carried by the racks 41c. The movement to and fro of the spindles 1, is effected by a pinion 45c meshing with a rack 46c.

When the cops are ready, the cop handling unit is lifted by means of handle lever 42 and the arms 40a, 40b from the position shown in Fig. 11 to that shown in Fig. 12, and subsequently the spindles 1 are retracted, so that the spools 31a are released by the action of stripping faces 38 and fall into the trough 52. When this has been done the cop handling unit is moved to the extent of half the distance between two spindles, so that a tube is placed in front of each spindle, as shown by broken lines in Figs. 11 and 12. The spindles are then moved forward from the position shown

in Fig. 12 to that shown in Fig. 13, and pick up the tubes, whereupon the cop handling unit is moved back to the position shown in Fig. 14, by the manipulation of handle lever 42. In this case one longitudinal wall 34b of the part X may be provided, at the point where its notches 38 engage over the spindles, with knives 84, the object of which is to cut the thread before the cops are stripped off. This cutting is effected by turning the spindle 1, as this conveys the thread towards the cutting edge of the knife 84.

In Figs. 15 and 16 this part of the device is shown to a larger scale.

The example shown in Figs. 17 to 20 deals with the case in which the device X is movable only in the direction of the spindle axis. The container 52 with the conveyor 99 and the axial shift by rack 41a and pinion 45 are the same as in the embodiments shown in Figs. 1-16. The part X, however, carries a table 90, with recesses for receiving the tubes 37, which rest against a rail 90a. On the bottom face of the table there are bars 93 (in this example one for each spindle) with longitudinal slots 93b for engaging over guides 91, 92 fixed to the table, so as to allow movement in the direction of the spindle axis. On the end facing the spindle each bar has a part 93a engaging behind the spool, and a pin 94 behind which a hook lever 96 engages. All the hook levers 96 of those spindle groups which belong together, or all the spindles on one side of the machine, are mounted on a shaft 95, which can be rotated through a definite angle by a hand lever 97. When the winding of the spool 37a is completed, and after release of all the bars 93 by the movement of the lever 97, the rack 41a and the pinion 45 move the part X with the table 90 to the left, in which movement all the bars 93 participate. They strip the spools 37a from their spindles and allow them to fall into the container 52, as shown in Fig. 19. The part X with the table 90 and the container 52 is then moved back. In this movement the bars 93 take part until they strike against the holders of the spindles. The table 90 with the container 52 moves together with the rack 41a, under the action of the pinion 45, farther to the right, into the position shown in Fig. 20, whereby the tubes 37 are pushed on to the spindles. In this position the lever 97 is moved back so that the hook levers 96 engage behind the pins 94 (Figs. 17 and 18). When this has taken place the part X, with the containers 52, moves back into the position shown in Fig. 17, so that the process of spooling can be resumed. Instead of providing a bar 93 for each spindle there may be only two bars for one group of spindles, the two bars being connected at 38 by a cross bar common to the group of spindles, the cross bar having for each spindle a recess 38 for stripping off the finished spool.

In the example shown in Figs. 17 to 20 there is, it is true, some reduction of accessibility to the thread, but this is not of any importance, having regard to the compact construction of the cop handling device; in any case, however, it is the simplest form of construction of the cop handling device X.

Figs. 21 and 22 show in somewhat more detailed form the actuating mechanism for the cop handling device. The cranks 40a and 40b are pivoted on their shafts 41a, 41b, and are coupled with each other, for example by tie rods 43. The movement of the shaft 41a takes place, as already mentioned, by means of the lever 42. The cranks are provided with rollers 39a and 75

39b, by which they engage under the longitudinal walls 34a, 34b. The longitudinal movement of the cop handling device X is limited by stops 50a on bar 48a, for which the guide slot 49 (see 5 Figs. 1, 3, 5, etc.,) is provided in the front wall 35a.

In Fig. 21 the mechanism is in its lower position at which time the spindles execute the winding operation. By rotating the hand lever 42 and 10 giving a quarter turn of the crank arms 40a and 40b in the direction of the arrow a, the part X is raised to the position shown in broken dash lines, and at the same time it is moved to the extent of half the pitch of the spindles, so 15 that the notches 38 engage the spindles behind the cop spools. This unitary arrangement of the lever mechanism causes both a vertical and a lengthwise movement of the part X to be produced by a single actuation of the lever mechanism. 20

By a partial return movement of the lever 42 the part X is first moved back lengthwise, so that the previously distributed tubes are disposed in front of the spindles in preparation for their 25 mounting upon the spindles in the manner described above.

Fig. 22 shows how, instead of the cranks 40a, 40b, cams 98 may be used, having exactly the same effect. In this case the cams on the shaft 30 41b are moved by those on the shaft 41a, through the medium of a rod 43.

Owing to the fact that the troughs 52 and also the conveyor 99, perform at least the movement in the direction of the spindles with the 35 part X, the trough and the conveyor are not only always held in the right position to receive the cops, but both parts, during the working of the machine, are pushed inwards under the spindles. If the trough and the conveyor were 40 stationary, as hitherto, then the trough and the conveyor would have to be in a position which would considerably widen the machine.

As already stated with reference to Figs. 11-14, the trough 52 for receiving the spools may be 45 provided at its bottom with a conveyor by which the spools are conveyed to a collector. In order, however, that the conveyance of the spools to the collector and their distribution in the latter should take place in a proper and regular way, 50 the conveyor, consisting for example of an endless band 99, is provided as shown in Figs. 23-25 with cross bars 109, between which the cops are placed. The movement of the conveyor band is, as already mentioned, produced by rollers 99a, one of which is driven by any suitable means. For conveying the spools to the collector 11, the device X may be provided with a feed pipe or feed channel 110, as shown in Figs. 23 and 24. 55 The collector is moved to and fro mechanically under the channel 110, by means of rack gear 111a and a cam disc 111b.

Fig. 25 shows another example of this device, according to which the container 111 is stationary while the feed channel 110 is provided with a 60 hopper and is swung to and fro above the container 111, by the agency of the cam disc 111b, whereby the spools are distributed side by side in the container.

What we claim as our invention and desire to 70 secure by Letters Patent of the United States is:—

1. In a cop winding machine, a group of spindles; a cop handling unit comprising stripping faces adapted to engage all the cops on said

spindles at once and supports for empty cop tubes spaced according to the positions of said spindles, and means whereby said spindles and said unit can be given relative movements axially of the spindles in one direction for stripping finished 5 cops simultaneously from said spindles, and in the opposite direction for charging said spindles simultaneously with the empty tubes on said supports.

2. A cop winding machine as described in 10 claim 1, wherein cutting means are provided to sever the thread as the cops are stripped from said spindles.

3. In a cop winding machine, a group of 15 spindles; a cop handling unit comprising stripping faces adapted to engage all the cops on said spindles at once, supports for empty cop tubes spaced according to the positions of said spindles, and means to receive the finished cops doffed from said spindles; and means whereby said 20 spindles and said unit can be given relative movements axially of the spindles in one direction for stripping finished cops simultaneously from said spindles, and in the opposite direction for charging said spindles simultaneously with the empty 25 tubes on said supports.

4. In a cop winding machine, a group of spindles; means for rotating said spindles, thread guides cooperating with the respective spindles, 30 means for reciprocating said threaded guides in unison; a cop handling unit comprising stripping faces adapted to engage all the cops on said spindles at once, and supports for empty cop tubes spaced according to the positions of said 35 spindles; and means whereby said spindles and said unit can be given relative movements axially of the spindles in one direction for stripping finished cops simultaneously from said spindles, and in the opposite direction for charging said 40 spindles simultaneously with the empty tubes on said supports.

5. In a cop winding machine, a row of spindles; a cop handling unit comprising stripping faces adapted to engage all the cops on said spindles at once and supports for empty cop tubes spaced according to the positions of said spindles, said supports being normally displaced from the plane containing the axes of said spindles; means whereby said spindles can be given 45 relative movements axially of the spindles in one direction for stripping finished cops simultaneously from said spindles, and in the opposite direction for charging said spindles simultaneously with the empty cop tubes on said supports; and means whereby said unit can be moved perpendicularly to said plane to bring the empty 50 cop tubes on said supports into alignment with their respective spindles.

6. In a cop winding machine, a group of spindles; a cop handling unit comprising stripping faces adapted to engage the cops on said spindles all at once and supports for empty cop tubes, alternating in position with said stripping faces; means whereby said unit can be moved transversely to the axes of said spindles to position first said stripping faces and then said supports in cooperative relation to said spindles; and means whereby said spindles and said unit can be given relative movements axially of the spindles in one direction for stripping finished 65 cops simultaneously from said spindles, and in the opposite direction for charging said spindles simultaneously with the empty cop tubes on said supports.

7. In a cop winding machine, a row of spindles; a cop handling unit comprising stripping faces adapted to engage all the cops on said spindles at once, and supports for empty cop tubes alternating in position with said stripping faces; means whereby said unit can be moved substantially perpendicularly to the plane containing the spindle axes; means whereby said unit can be moved perpendicularly to the spindle axes in the plane containing said axes to position first said stripping faces and then said supports in cooperative relation to said spindles; and means whereby said spindles and said unit can be given relative movements axially of the spindles in one direction for stripping finished cops simultaneously from said spindles, and in the opposite direction for charging said spindles simultaneously with the empty tubes on said supports.
- 10 8. In a cop winding machine, a group of spindles, a cop handling unit movable axially of said spindles and comprising supports for holding empty cop tubes in properly spaced relation to be placed simultaneously upon said spindles, and stripping devices adapted to engage all the cops on said spindles at once and movable with respect to said supports to permit the latter to be withdrawn while said stripping devices remain in operative relation to the cops.
- 15 9. In a cop winding machine, a group of spindles; a cop handling unit comprising stripping faces adapted to engage all the cops on said spindles at once and supports for empty cop tubes spaced according to the positions of said spindles, and means for moving said spindles axially in one direction for stripping finished cops simultaneously from said spindles, and in the opposite direction for charging said spindles simultaneously with the empty cop tubes on said 10 supports.
- 10 10. A cop winding machine as described in claim 9, wherein means are provided for moving said cop handling unit transversely to the spindle axis to bring either said stripping faces 15 or said supports into operative relation to said spindles.
11. In a cop winding machine, a group of winding spindles, means for rotating said spindles, means for moving said spindles axially in unison, 20 a cop handling unit comprising stripping faces adapted to engage the cops on said spindles to hold the cops as said spindles are withdrawn by said axially moving means, and cutting means adapted to sever the thread as the cops are 25 stripped from said spindles.

WILHELM REINERS.
GUSTAV KAHLISCH.
